UNITED STATES PATENT OFFICE.

JOHN STEMBER, OF NEW YORK, N. Y.

DESIGN FOR A BELT.

SPECIFICATION forming part of Design No. 33,721, dated December 11, 1900.

Application filed November 19, 1900. Serial No. 37,070. Term of patent 3½ years.

To all whom it may concern:

Be it known that I, JOHN STEMBER, a citizen of the United States, and a resident of the city of New York, borough of Manhattan, in 5 the county and State of New York, have invented and produced a new and original Design for a Belt, of which the following is a full, clear, and exact description.

The leading features of the design consist 10 in the shape of the ornamental front panel A, which appears embossed on the body B of the belt and presents a pointed center and side members which curve upward from the pointed center, and in the button-like ornaments 15 C, arranged longitudinally along the side members of the panel.

The minor features of the design consist in

the shape of the body B, which body is of greatest width at its rear center, from which point the body gradually curves on diminishing lines in the direction of the panel. 20

Having thus described my invention, I claim as new and desire to secure by Letters Patent—

The design for a belt herein shown and described. 25

In testimony whereof I have signed my name to this specification in the presence of two subscribing witnesses.

JOHN STEMBER.

Witnesses:

J. FRED. ACKER,
JNO. M. RITTER.
